UNITED STATES PATENT OFFICE.

WILLIAM B. MOORE, OF CHICAGO, ILLINOIS, ASSIGNOR TO JUDSON E. WRIGHT, OF SAME PLACE.

PREVENTING INCRUSTATION.

SPECIFICATION forming part of Letters Patent No. 371,896, dated October 18, 1887.

Application filed December 18, 1886. Serial No. 221,972. (No model.)

To all whom it may concern:

Be it known that I, WILLIAM B. MOORE, of the city of Chicago, in the county of Cook and State of Illinois, have invented certain new and useful improvements in receptacles for containing compounds or compositions for preventing incrustations in steam-boilers and in devices used in connection with said receptacle for automatically feeding said composition, 5 when dissolved, to the water in the boiler in the proportion in which it may be required, of which the following is a specification.

My invention has relation to and consists of certain improvements in the receptacle and 15 devices for preventing incrustations in steam-boilers described and shown in the specification forming a part of Letters Patent No. 293,172, issued to Edward J. Hoffman and others on February 5, 1884. The interior of 20 the receptacle described in said specification, and of which this is an improvement, is divided longitudinally into compartments, which contain the non-incrustating compound, which compound as it is gradually dissolved is fed 25 to the water of the boiler by the ends of a coiled spring and by the projecting ends of twisted wires through apertures in the ends of the receptacle. This form of constructing the receptacle and method of feeding the compound to the water experience has shown to 30 be imperfect and its working unsatisfactory. No means were provided for protecting the orifices through which the feed is made from the compound, which, being of a gummy nature, soon clogged said orifices and rendered 35 the feed irregular.

My improvements consist in removing from 40 said receptacle the diaphragms dividing the same into several chambers or compartments and dispensing with the coiled spring and twisted wires, and in inserting two or more small tubes, which, preferably, are placed against the inner side of the receptacle opposite each other, and are soldered thereto. 45 These tubes extend from the bottom of the receptacle to within a very short distance of the top or cover, and are closed at the bottom and soldered to the bottom of the receptacle, and are open at the top. Small orifices are made 50 in the bottom of the receptacle into the tubes,

and also through the cover above the tubes, through which a wire is passed.

In the drawings, Figure 1 represents a section of a steam-boiler with said receptacle suspended in the water from one of the boiler-tubes. Fig. 2 is a longitudinal sectional view of said receptacle with my improvement shown therein. Fig. 3 is an end view showing a portion of the cap broken away. 55

Referring to said drawings, A is the receptacle.

B B are the tubes secured therein, as above described.

C is a wire passing through the orifices a a and a' a' into the tubes B B, and extending 65 through the same and forming a loop on either end of the receptacle.

G is the non-incrustating compound.

F is a filtering material of curled shavings or some other suitable material placed over 70 the top of the non-incrustating compound.

E E are the boiler-tubes, and c c are wires by which the receptacle is suspended in the water.

The method of using my improved receptacle and its operation are as follows: The receptacle is filled with the non-incrustating compound G to within about an inch of the top. The space above the compound and the cover f is then filled with some suitable material—such as curled shavings—which will act as a filter for the compound when it liquefies. The wire C is then passed through the orifices a a in the bottom of the receptacle, and up through the tubes through the 85 orifices a' a' in the cover. The cover is then soldered fast on the can, and the wires looped over the same and the ends twisted together. The case as thus prepared is passed through the hand-hole or man-hole in the boiler and 90 suspended by wires or hooks from one of the boiler-tubes.

To obtain the most satisfactory results the receptacle should be suspended in the water near the front of the boiler, with the bottom 95 of the case nearest the front of the boiler and the end with the cap suspended a little lower than the bottom. The compound as it becomes liquefied by the water which passes through the orifices a a and a' a' into the space 100

above the compound will be gradually fed out by the wire C through the orifices a a' . The amount or rapidity of the feed is regulated by the space between the cap and the end of the 5 tubes. If a rapid feed is desired, this space is made wider than where a slow feed is required.

I use different compounds for different waters, and where the compound liquefies quickly 10 I make the tube longer and the space between the end of the tube and the cap consequently less than when the compound liquefies slowly.

Having now fully described my invention, what I claim as new, and desire to secure by 15 Letters Patent, is—

1. In a receptacle for containing compounds for preventing incrustations in steam-boilers,

the tubes B B, having the orifices a a' a' opening therein, and the wire C, passing through the same, said tubes being a little shorter than 20 the receptacle and having their lower ends closed and their upper ends open, for the uses and purposes and in the manner substantially as specified.

2. In devices for preventing incrustations 25 in steam-boilers, the combination of the outside case or receptacle, A, with the tubes B B and the wire C, arranged substantially as and for the uses and purposes specified.

WILLIAM B. MOORE.
